UNITED STATES PATENT OFFICE.

WILLIAM SAXON, OF OAK PARK, ILLINOIS, ASSIGNOR TO MIEHLE PRINTING PRESS
& MFG. COMPANY, OF CHICAGO, ILLINOIS, A CORPORATION OF ILLINOIS.

PRINTING PRESS.

Application filed June 15, 1922. Serial No. 568,486.

To all whom it may concern:

Be it known that I, WILLIAM SAXON, a citizen of the United States, residing at Oak Park, in the county of Cook and State 5 of Illinois, have invented certain new and useful Improvements in Printing Presses, of which the following is a specification.

This invention relates to printing presses.

In multi-color work it is absolutely essential 10 that perfect register is obtained for the reason that a sheet of material receiving the impression in different colors must be run through the press a plurality of times, depending upon the number of different colors 15 used. If register is not perfect the colors will overlap, thereby ruining the work. The movement of the type bed has considerable to do with registering, that is to say, if the type bed were permitted any lateral shifting 20 movement the colors would overlap each other and spoil the work.

Heretofore in the vertical type of printing press similar to that illustrated herein, the type bed has been given a vertical reciprocating movement from a crank shaft through a single centrally arranged connecting rod. By using such a single connecting rod there is a possibility of the type bed slightly moving or angling out of its proper aligned 30 position, resulting in bad register, as mentioned hereinabove.

Again, with the use of the single central connecting rod for transmitting vertical reciprocating movement to the type bed, it is 35 structurally impossible to mount a pile delivery table which is capable of lowering in a vertical line as it receives impressed material unless such table is moved rearwardly of the press an excessive amount, which 40 would make necessary an excessive throw or movement of the delivery grippers. The throw of such grippers is to be limited as much as possible, especially for high speed work of the nature to be accomplished by 45 a press of the type herein disclosed.

Accordingly, one object of this invention is to provide simple, efficient and reliable driving mechanism for the type bed whereby the latter may be maintained in proper 50 alignment to facilitate good registering action.

Another object is to provide driving mechanism for the type bed which will permit the use of a pile delivery table capable of 55 downward vertical movement as it receives

impressed material and in close proximity to the bed, thereby reducing the throw of the delivery grippers.

These and other objects are accomplished by means of the arrangement disclosed on 60 the accompanying sheets of drawings, in which—

Figure 1 is a fragmentary side elevation of a vertical printing press embodying my invention; and 65

Figure 2 is a rear elevation of the same, some of the parts being shown in section.

The various novel features of the invention will be apparent from the following description and drawings, and will be particularly pointed out in the appended claims. 70

Referring to the figures of the drawings, it will be noted that I have disclosed my invention in connection with a vertical type of printing press including a main frame 10 and a way frame 11 in which the type bed 12 and the cylinder frame 13 are given simultaneous vertical reciprocatory movements in opposite directions. In this connection the type bed has associated therewith 75 a rack 14 and the cylinder frame has connected therewith a rack 15, both of which racks mesh with a rotary but otherwise stationary gear 16. The driving power is received from a crank shaft 17 mounted in 80 pedestals 18' formed integrally with the main frame 10 of the press. Said shaft 17, as shown, has two cranks 18 to the outer end of each of which is pivotally connected 85 connecting rods 19, which rods in turn are connected to pins 20 mounted in brackets 21 secured to the type bed 12. In this connection it will be noted that the connecting rods 19 are spaced the maximum distance 90 apart permissible and still maintain the connecting rods in proper position and within the confines of the frame of the press. These connecting rods are operatively connected to points near the outer sides of the type bed 12 so that as the type bed is reciprocated 95 back and forth in a vertical direction, the type bed 12 is maintained in proper alignment, as distinguished from any lateral skewing or angling movement. Of course 100 the type bed 12 is mounted in the ways of the way frame with proper rigidity, but if a single central connecting rod were provided for transmitting vertical movement to the type bed, as distinguished from the double connecting rod arrangement shown, there 105

110

world be a tendency, and, as a matter of fact, the type bed would at least in time, move out of alignment. This tendency to angle and skew or get out of alignment 5 would wear the ways, permitting an increased amount of freedom, resulting in increased skewing and bad register. However, by means of the double connecting rod arrangement shown, the type bed is reciprocated back and forth in a vertical direction 10 in perfect alignment, so that register, so far as the type bed is concerned, will be perfect.

Again, by spacing the connecting rods 19 a maximum distance apart provision is made 15 for receiving the pile delivery table 22 therebetween, so that such table may lie in close proximity and directly in the rear of the type bed 12. Such arrangement also permits of the use of a pile delivery table 20 which may lower in a vertical line automatically in accordance with material piled thereon, and still leave all the necessary clearance.

By thus being able to place the pile delivery table directly adjacent and to the rear 25 of the type bed 12, the throw of the delivery gripper arms 23 is greatly reduced,

which increases the output of the machine for a given speed.

It is my intention to cover all modifications of the invention falling within the spirit and scope of the following claims.

I claim:

1. In a vertical type of printing press, the combination of a type bed, a pile delivery table to the rear of said bed, a driving member, and connecting rods operatively connecting said type bed and driving member and spaced apart for accommodating said pile delivery table as it is lowered between said connecting rods directly in the rear of said type bed.

2. In a vertical type of printing press, the combination of a type bed, a pile delivery table to the rear of said bed, a driving member, and power transmission members connecting said type bed and driving member and spaced apart to accommodate said pile delivery table as it is lowered between said transmission members directly in the rear of said type bed.

Signed at Chicago, Illinois, this 22nd day of May, 1922.

WILLIAM SAXON.
